SAFETY RAZOR AND BLADE THEREFOR

Gordon C. Arey, Indian Hill, Ohio

Application December 28, 1935, Serial No. 56,518

5 Claims. (Cl. 30—34)

This invention relates to razors, and is particularly directed to improvements in safety razors of the type employing a wafer-like blade clamped between holding elements. More specifically the improvements relate both to the holder and to the blade.

There are a great many wafer type blades and holders therefor on the market today. It is a known fact that users are extremely dissatisfied 10 with this type of blade because it does not remain sharp any length of time. This is evidenced by the fact that they are continually changing from the blade of one manufacturer to the blade of another, and are ready to try newly 15 marketed blades the moment they are placed on the market.

It frequently occurs that a blade of this type is unfit for further use after the first or second shaving. It is fundamentally impossible to make 20 a wafer blade which will last any length of time. The thinness of the metal itself precludes durability. This condition cannot be remedied for the reason that the blades must be of thin stock in order to be flexible and to sell at the extremely 25 low prices at which they are sold.

The blades have been furnished with two sharpened edges, and the holders therefor secure the blades in position exposing both edges so that 30 the user is able to shave with either edge during a given shaving operation. Both edges being available, it is obvious that they are both used at a given shaving operation, and both are dulled approximately the same amount. Following the 35 first shaving operation the blade is placed in the holder indiscriminately, that is, it may go in the same way as the first time, or it may be placed in position with its faces reversed, or it may be reversed end for end, or both. Thus there are four positions possible.

It follows that if the blade is turned over, the 40 second shave will be moderately good. However, it is obvious that there is no way of determining whether or not it has been turned over. Therefore it may be generally stated that the efficiency 45 of the blade decreases with each shave unless, perchance, the blade has been turned over accidentally.

These blades are flexed when held in the holder 50 so that the edges are turned in the direction of movement in use. Accordingly, if turned over, the flexing is reversed and the cutting is better since the cutting pressures tend to push back any turned metal at the edge (microscopically speaking). Even if the blade is turned over properly 55 after the first shave, only two good shaves can be procured.

It is the object of the present invention to provide a holder and blade combination wherein the user is able to discriminate as to the position 60 in which he places the blade, that is, in which

means is incorporated informing him as to those positions in which the blade has been used and enabling him to procure a new edge as many as four times.

More specifically, it is an object of the invention to provide that the blade is automatically marked to indicate use at a given position without any attention whatsoever on the part of the user.

It is a further object of this invention to provide an improved blade, which blade is formed so that it can be operated upon by the holder with the purpose of identifying any used position.

It is a still further object to provide an improved blade and holder, wherein only one edge 10 of a double edged blade is exposed at a time, and whereby it is possible to use the exposed edge twice, that is, to use the blade one way and then to reverse its face, and wherein it is possible to reverse the blade end for end and use the other edge two times in the same manner, thus guaranteeing the purchaser of the blade at least four 15 good shaves, each used position being automatically identified.

It is a still further object of this invention to provide a holder for a doubled edged blade which 20 flexes only one side portion at a given time or position of the blade in the holder.

It is a still further object of this invention to provide an improved blade of this type in which 25 the various positions in which the blade has been used are identified, and which may incorporate the manufacturer's trade-mark as a part of the means for used position identification.

Other objects and further advantages will be 30 more fully apparent from a description of the accompanying drawing, in which:

Figure 1 is a general view of the improved holder and razor blade, showing the parts fully 35 assembled for a shave, and a portion thereof in section for illustrating the blade marking device.

Figure 2 is a transverse sectional view of the 40 holder elements of the improved holder with the blade interposed therebetween, this view showing the parts prior to marking of the blade for identifying the used position.

Figure 3 is a bottom plan view of the top holder 45 element, showing the blade punching member.

Figure 4 is a plan view of the improved blade.

Figure 5 is a top plan view of the lower holder 50 element, showing the recess cooperating with the punching member.

Figure 6 is a fragmentary enlarged sectional view showing the blade punching means of the holder in position for action on the blade.

Figure 7 is a view similar to Fig. 6, showing the 55 process of punching the blade.

Figure 8 is a view similar to Fig. 6, but showing the blade punched out and the position identified.

Figure 9 is a plan view of a slightly modified 60

blade of this invention, showing the portions to be punched out formed by the letter G, showing a means whereby a manufacturer can identify his blades.

5 Figure 10 is a view taken similar to Fig. 6, but showing a passage through one holder element through which the punching can pass clear of the holder.

Referring to the drawing, it will be noted that 10 in the present embodiment of the invention the holder shown comprises three parts. Holder or clamping elements 15 and 16 are provided, these elements being forced together for clamping the blade 17 therebetween by means of a screw-threaded handle element 18. The general arrangement of the holder elements with the handle cooperating with a screw-threaded stud on one holder element for forcing the holder elements together on the blade is well known.

20 The lower holder element 15 includes the screw-threaded stud 19 disposed centrally thereof and a longitudinal rib 20 extending toward each end of the element from the central stud, but stopping short of the ends thereof. The stud and rib 25 locate the blade on the holder element when the blade is placed on the lower holder element as shown in Figure 2. For this reason the blade includes a slot 21 disposed longitudinally thereof having a circular central portion, the slot thus 30 formed being complementary to the rib and stud of the holder element 15 so as to fit thereover. Any slot and lug arrangement or other means may be used centrally of the holder element and blade for the purpose of locating the blade and preventing rotation thereof on the holder element.

35 The upper holder element 16 includes an aperture 22 through which the stud projects and a groove 23 fitting over the longitudinal rib of the lower holder element, whereby the two elements 40 can be moved in close relationship against the thin wafer-like blade interposed therebetween.

45 Lugs 24 at the corners of the holder element cooperating with notches 25 in the corners of the blade further assist in locating the blade in position. The advantages of the guiding and locating means, that is, the slots and notched corners in the blade and the cooperating lug and slots on the holder elements, need not be described in detail in this application since they form no part of 50 the present invention, the structure shown being selected solely for the purpose of showing a modern environment for the improvement.

55 Referring to Figures 1 and 2, it will be observed that the holder elements are formed so as to provide for exposure of only one edge of the double edged blade at one time. For this purpose the holder elements extend from the central longitudinal rib 20 a greater distance at one side than the distance from the center of the blade to the edges thereof. Because of this the blade rests, as 60 shown in Figure 2, with one of its sharpened edges lying within the edge margin of the lower element 15.

65 The upper element 16 includes a marginal flange 26 projecting downwardly a sufficient distance for engaging along the edge margin of the lower element as shown at 27 in Figure 1. This flange 26 stops short so as to clear the lugs 24 at each end of the lower element 15.

70 The upper clamping element 16 is longitudinally recessed as at 28, whereby a substantial margin of the blade at the side not being used is not engaged. Moreover, from the central slot of the blade toward the edge not in use at the time, 75 the blade is in flat condition so that it will be

observed as entirely unused until the blade is rotated to place this edge in use. This is true because no flexing of the metal occurs and the edge is fully protected against contact or use of any sort. Moreover, it is free of contact with any of the holder parts (see Figure 1). It is aptly described as contained or enclosed within a recess formed by the upper and lower elements.

On the opposite side of the central line the holder elements are curved for the purpose of 10 flexing the blade while in use, that is to say, the lower holder element has a curved upper surface and the upper element has a curved lower surface, which surfaces are formed on radii taken from the same center. The lower holder element is of less 15 width than the blade from the central lines of these parts, so that the blade projects slightly beyond the edge of the lower holder element as at 29.

The upper holder element has a serrated guard 20 edge 30 lying above the blade edge. This serrated guarding edge is formed so as to slightly clear the blade well back from its sharpened edge as at 31, whereby the blade is free to flex somewhat as the cutting edge is used. The serrated guard edge is 25 a conventional structure and its advantages need not be described.

Accordingly, it will be noted that only one edge 30 of the double edged blade is exposed for use, the other edge being protected by enclosure within the holder elements.

Referring to the blade, it will be seen that it includes a weakened portion 32 disposed toward each corner. It may be said that lines connecting the centers of the weakened portions would form 35 a rectangle. These weakened portions can be formed in a multitude of ways. As one selected mode of forming the same, the metal may be punched out to provide an almost complete circular slot 33 leaving a slight connecting portion 34 forming the central tangs 35 formed by the metal within the circular slots. These slots can be formed in any design desired. For example, for identifying the origin of the blade, as shown in Figure 9, they can be cut to form the letter G as 45 indicated at 36.

As shown in Figure 3, the upper holder element includes a pin or stud 37 projecting from its undersurface adjacent one corner thereof. A recess 38 is formed in the lower holder element opposite to and complementary to the stud 37 so that the stud will register therewith when the holder elements are placed together.

In reference to Figure 2, it will be noted that the stud and recess are adjacent one of the four 55 weakened portions of the blade when the blade is placed within the holder. Therefore, as the clamping or holding elements are forced together by the screw-threaded handle element 18 with the blade in position as shown in Figure 2, the stud will engage the tang 35 forcing it into the recess and snapping it off as the parts are clamped together. The steel of which the blades are formed lends itself admirably for this purpose since it will snap readily when flexed a certain 60 amount.

65 The operation of breaking off the tang can be fully appreciated by reference to Figures 6 to 8 inclusive. The recess 38 can, if desired, be in the form of a passageway as shown at 39 in Figure 10, whereby the punched out tang portion will drop out of the razor. The tangs are relatively small and are conveniently displaced from the holder upon each shaving operation.

70 From the foregoing description, it will be ob- 75

served that the effect of clamping the clamping elements upon the blade for the first time, that is, with a new blade, is to punch out one of the weakened portions. The next time the blade is picked up for use the shaver will at once know in which position he has used the blade, for if he puts it back in the same position it will be observed that punching has already occurred. He therefore, if that edge is dull, either turns 10 the blade end for end or reverses its faces. This brings another tang adjacent the punching elements and he knows without question that he is using a new edge.

In the treatment of the problem it is to be observed that the blade is considered as having four shaving edges, i. e., two for each sharpened edge. This is true for the reason that reversing the faces of the blade causes flexing of the side of the blade adjacent the cutting edge in the opposite direction. This permits use of the same edge from an opposite side with the result that an efficient shave is procured from the same sharpened edge of the blade.

By this means the user of the razor is able 25 to use it in four positions, the blade being automatically marked each time it is used, that is, the used position is fully identified, and he is able to shift the blade so as to use a new edge each time if he desires. Thus the manufacturer of the blade is able to guarantee at least 30 four perfect shaves with each blade. Moreover, he is able to identify his blade if he wishes to employ trade identification by forming the slots which make up the tangs in the form of letters 35 or any other trade insignia.

It can, of course be appreciated that this invention will have application to a safety razor and blade wherein both edges of the blade edge are exposed at the same time since the identification means can be used to a lesser extent, 40 that is, by the use of only two tangs or weakened portions of the blade for indicating whether or not the blade has had its faces reversed so that it can be definitely flexed in the opposite direction at the time of the second shave.

The present embodiment of the invention is readily applied to razor blades of the wafer type which are formed of a fairly hard steel such as are in current use today. The metal of these 50 blades is brittle enough to lend itself admirably for the use intended, that is, the tang portions will snap off readily when flexed a certain amount. It will of course be appreciated that the present application is intended to cover all 55 equivalent structures and other marking devices may be employed.

The present conception is that of means incorporated in a safety razor for marking the blade, whereby each used blade position is automatically marked for identification. The invention results in one sense from the determination that a marking means or device properly located in the holder elements will act to mark the blade a different point for each position of the blade. 60 In a further sense it has been determined that a double edge blade can be placed in a plurality of different cutting positions for varying the exposure or direction of the edge, and by means of the present identification device the user will be able to know in which positions he has used the blade and therefore which edges have been used.

The device in the holders may be of a design capable of marking the blade without special co-operating structure on the blade. However, it is considered more desirable to form the blade for cooperation in the act of marking and for this reason a blade has been conceived and is disclosed herein in one embodiment which is formed for ready marking.

Having described my invention, I claim:

1. In a razor, a pair of clamping elements, 10 means for forcing said elements together, a wafer-like blade of rectangular outline adapted to be interposed between said clamping elements, the opposite edges thereof sharpened, said holder enclosing one edge in position of use and flexing 15 the blade along the opposite edge so as to dispose the edge in the direction of use, said blade and clamping elements incorporating cooperating devices for marking the blade in each position of use, that is, with one or the other face 20 down with one edge exposed, or one or the other face down with the other edge exposed.

2. A blade for a safety razor, said blade having punched out portions at each corner forming tangs, said punched out portions forming designations to identify the blade as the article of a given manufacturer.

3. In a safety razor, a pair of clamping elements, a blade disposed between said elements, means for clamping the elements on the blade, 30 said elements including a stud and aperture respectively, said stud disposed toward one corner of the particular clamping element of which it is a part and adapted to register with the aperture in the other clamping element, and said blade 35 having punched-out portions at each corner providing tangs, said tangs adapted to be broken off to permit passage of said stud therethrough at a different point for each position of the blade between the clamping elements.

4. In a safety razor, a pair of clamping elements, means for securing said clamping elements together, said clamping elements including a punching device disposed toward the ends of the clamping elements, and a razor blade interposed between said clamping elements, said blade having a plurality of tangs thereon positioned for successive engagement by the punching device, said punching device and the blade cooperating for engagement of the punching device with the tangs of the blade, one at a time and in succession for breaking off the respective tangs as the blade is moved through successive positions in the clamping elements.

5. In a safety razor, a pair of clamping elements, means for forcing said elements together, a wafer-like blade of rectangular outline adapted to be interposed between said clamping elements and having its opposite edges sharpened, said clamping elements incorporating a punching device located toward one end of the assembled clamping elements for marking the blade in its respective positions of use, said blade incorporating a plurality of weakened removable portions thereon, said weakened portions engaged one at a time by said punching device for breaking the same and identifying the respective positions in which the blade has been placed between the clamping elements.
